UNITED STATES PATENT OFFICE

2,470,343

WALL TABLE STRUCTURE

Fred K. Dinger, Chisholm, Minn.

Application September 9, 1948, Serial No. 48,513

3 Claims. (Cl. 311—19)

1

This invention relates to new and useful improvements in table structures and the primary object of the present invention is to provide a novel and improved collapsible table structure which is quickly and readily assembled or disassembled in a convenient manner.

Another important object of the present invention is to provide a hinged panel or table top and embodying novel and improved means for supporting and locking the same in a substantially horizontal position when in use.

A further object of the present invention is to provide a table structure that is extremely neat and attractive in appearance and small and compact in structure.

A still further aim of the present invention is to provide a collapsible table structure that is simple and practical in construction, strong and reliable in use, relatively inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a perspective view of the present table structure and showing the same collapsed or in unused position;

Figure 2 is a perspective view of the present table structure and showing the same in position for use;

Figure 3 is a side elevational view of Figure 1;

Figure 4 is a side elevational view of Figure 2 and showing the hinged panel in a partially raised position;

Figure 5 is a fragmentary perspective view showing the hinged panel in a partially raised position;

Figure 6 is a fragmentary longitudinal vertical sectional view taken substantially on the plane of section line 6—6 of Figure 5;

Figure 7 is a fragmentary perspective view of the hinged panel that is used in conjunction with the present invention; and

Figure 8 is a view similar to Figure 6 and showing the hinged panel in a locked position.

Referring now to the drawings in detail, wherein, for the purpose of illustration, there is disclosed a preferred embodiment of the present invention, the numeral 10 represents the wheeled or movable support that is used in conjunction with the present invention generally, and includes an upper wall 12, a lower wall 14, an intermediate wall 16

2

that is spaced parallel to the upper and lower walls 12 and 14 and a rear wall 17.

A pair of spaced parallel side members or posts 18 and 20 are fixed to and support the walls 12, 14 and 16 in their intended position, and auxiliary posts or braces 22 and 24 are disposed between the upper wall 12, the intermediate wall 16, and the bottom wall 14, and intermediate wall 16, respectively.

10 Obviously, any suitable number of walls may be employed to properly support books, vases, or the like, and the walls may be suitably colored or decorated to add to the attractiveness of the same. The walls 12, 14, and 16 are preferably provided 15 with arcuate forward edges 26. However, any suitable shape may be employed without deviating from the scope of the present invention.

The numeral 28 represents a substantially semi-circular anchor member, the lower straight, substantially horizontal edge 30 of which is hinged, as at 32, to one transverse edge 34 of a substantially rectangular panel or table top 36.

Guides 38 are secured to the longitudinal side edges 40 of the hinged panel 36 and are slidably 20 received in vertical, channel-shaped slots 42 provided in the opposed, inner faces of the side members 18 and 20, as shown best in Figures 5, 6, and 7 of the drawings.

Secured to the under surface of the upper wall 30 12 and conforming to the shape thereof is a retaining wall 44 having an upwardly inclined rear edge 46.

The rear edge 48 of the upper wall 12 is provided with an elongated notch to form a longitudinal edge 50 and the under surface of the upper wall 12 is notched, as at 52, to provide a channeled opening 54 between the upper wall 12 and retaining wall 44 that will receive the reduced transverse edge 56 of the hinged panel 36 when the latter is in a raised and substantially horizontal position.

The guide slots 42 are enlarged and rearwardly inclined at their upper ends 58 to permit the extension or edge 56 to engage the channeled opening 54.

Angulated stop plates 60 are fixed to the under surface of the hinged panel 36 and include inclined portions 62 that engage the inclined edge 46 of the retaining wall 44, and free portions 64 50 that bear against the lower face of the retaining wall 44 when the hinged panel 36 is raised.

In order to lock the hinged panel 36 in a raised and substantially horizontal position, there is provided a pivotal latch 66 having a hook portion 68 that will engage the shank portion of a

headed pin or lug 70 that projects from the lower face of the hinged panel 36.

It should be noted that when the hinged panel 36 is disposed in a raised and locked position, the upper surface of the same is flush with the upper surface of the upper wall 12.

A suitable number of wheels or casters 72 are carried by the bottom wall 14 and permit the support 10 to be conveniently moved for raising and lowering the hinged panel 36.

In view of the foregoing description taken in conjunction with the accompanying drawings, it is believed that a clear understanding of the device will be quite apparent to those skilled in this art. A more detailed description is accordingly deemed unnecessary.

It is to be understood, however, that even though there is herein shown and described a preferred embodiment of the invention, the same is susceptible to certain changes fully comprehended by the spirit of the invention as herein described and within the scope of the appended claims.

Having described the invention, what is claimed as new is:

1. A table structure comprising a wheeled support having an upper substantially horizontal wall and a pair of spaced side members, an anchor member secured to a supporting structural element, a substantially rectangular panel hinged at one end to said anchor member, guide slots provided in said side members, guides carried by said panel slidably received in said slots, the under surface of said upper wall having an elongated notch, a reduced extension at the free end of said panel receivable in said notch for supporting said panel coplanar with said upper wall, and means for locking said panel to said upper wall.

2. The combination of claim 1, and stop means limiting the sliding movement of said guides in said slots, said stop means including a plurality of angulated plates carried by said panel and having portions projecting outwardly from the free end of said panel.

3. A table structure comprising a support having an upper flat wall and a pair of side members, an anchor member secured to a supporting structural element, a panel hinged to said anchor member, guide slots provided in said side members, guides carried by said panel slidably received in said slots, the under surface of said upper wall having a notch, a reduced extension projecting from said panel and received in said notch for supporting said panel substantially coplanar with said upper wall, and means for locking said panel to said upper wall.

FRED K. DINGER.
